UNITED STATES PATENT OFFICE.

BARTHOLOMEW E. McSHEEHY, OF JERSEY CITY, NEW JERSEY, ASSIGNOR TO STEPHEN T. WILLIAMS & STAFF, LIMITED, OF BOSTON, MASSACHUSETTS, A COPARTNERSHIP COMPRISED OF STEPHEN T. WILLIAMS AND BARTHOLOMEW E. McSHEEHY.

TYPE-WRITING MACHINE.

No. 893,860.

Specification of Letters Patent.

Patented July 21, 1908.

Application filed June 12, 1905. Serial No. 264,824.

To all whom it may concern:

Be it known that I, BARTHOLOMEW E. McSHEEHY, a citizen of the United States, residing in Jersey City, in the county of Hudson and State of New Jersey, have invented certain new and useful Improvements in Type-Writing Machines, of which the following is a specification.

This invention relates to typewriting machines, particularly those of the front-strike variety, and its object is to facilitate the introduction of sheets between the revoluble platen and the usual devices which guide and feed the paper around beneath the platen, particularly where it is desired to assemble together several sheets of different shapes and sizes in a special relation to one another with intervening carbon sheets, or where it is desired to insert sheets that are pasted together, or so assembled, so that they will not conveniently enter the bite of the usual pressure rollers. To accomplish this purpose I make provision for lifting the revoluble platen away from the paper guiding and feeding devices that are usually mounted beneath the platen. Thus ample space is left for the introduction of paper at either the front or back of the platen between the same and said guiding and feeding devices. In order to insure the regularity or evenness of the written lines, I contrive to lock the platen down in normal position, while permitting it to rotate for line-spacing. Moreover in order to permit the operator to have both hands free for the insertion of the paper when the platen is elevated, I provide means for mechanically detaining the platen in its elevated position.

Other objects and advantages will herein-
after appear.

In the accompanying drawings, Figure 1 is a sectional view of the platen frame at the right hand end thereof, indicating the platen by a dotted circle and showing the platen axle in section. Fig. 2 is a view similar to Fig. 1, showing the platen as elevated so as to permit introduction of sheets, and also showing in dotted lines the usual devices for casting off the pressure rollers. Fig. 3 is an elevation of the left-hand end of the platen frame and paper carriage, the parts shown in full lines in normal position, and the platen being shown in dotted lines in elevated posi-

tion. Fig. 4 is a plan of the platen frame with appurtenances.

The invention is shown applied to the well known "Underwood" typewriting machine, in which the type bars 1 strike rearwardly against the front side of a revoluble platen 2; the latter having an axle 3, extending through the ends 4, 5 of a platen frame and carrying finger-wheels 3^a; said frame also including a rear paper shelf 6, which extends down beneath the platen and curves up in front thereof at 7 to serve as a guide for directing the paper forwardly and upwardly around the platen. To feed the paper either forwardly or backwardly, rolls 8, 9 are also provided to bear against the under and front sides of the platen.

For lifting the platen I provide a pair of three-armed members, one at each end of the platen, and each comprising arms 10, 11 and 12. The arms 10 are rigidly united by a bar 13, which extends along the platen at a considerable distance from the front thereof. The pair of arms 10 taken with the rigid connecting bar 13 form a bail, which is hinged upon pivot screws 14 threaded in ears 15 provided upon the ends of the platen frame. By means of the bar 13, the bail may be swung down and up about said hinge.

At their rear ends the arms 11, which form continuations of arms 10, are provided with slots 16 to engage the platen axle 3 and lift the same to the position seen at Fig. 2, so that when it is desired to lift the platen, it is only necessary to press down the bar 13. The platen ends are provided with slots 17, through which the ends of the platen axle 3 extend, the slots being of a form to permit up and down movements of the platen axle about the hinge 14. The platen is normally locked down by means of a pair of latches 18 pivoted at 18^a upon the ends of the platen frame, and catching directly over said axle, as at Fig. 1. This latch or lock is released during the downward movement of said bar 13; the arms 12 of the three-armed levers being for this purpose connected by a pair of links 19 to arms 20, formed upon said latch. When the levers turn upon hinge 14, the links 19 drive back the arms 20, and slip the latch back off from the axle. During this time there is no movement of the axle. This lost-motion of the three-armed members is

- provided for by said slots 16 in the arms 11. During the first part of the movement of said arms, while the links 19 are forcing the latch 18 off from the axle 3, the arms 11 move independently of the platen axle; and then the latter is engaged by the lower ends of the slots 16, and thereby elevated to the position seen at Fig. 2, the platen being thus carried clear of the paper guiding and feeding devices 6, 7, 8 and 9. It will be seen that the sheets, whether pasted together or otherwise assembled, may be readily inserted at either the back or front of the platen, and then the latter may be returned to position by simply raising the bar 13, whereby the paper is caught between the platen and the pressure rollers 8, 9, and may thereafter be fed either forwardly or backwardly in the usual manner.
- 20 In order to enable the operator to employ both hands in inserting sheets, I provide for mechanically holding the platen elevated in the Fig. 2 position. For this purpose the backward movement of the latch-arm 20 is opposed by a spring 21. It will also be seen that the members 19 form toggles, which, during the upward movement of the platen, pass the straight-line position, and thereafter the springs 21, acting upon the arms 20, operate through the links 19 to elevate the arm 12. These springs 21 are sufficiently strong to support the weight of the platen, so that the latter is prevented from dropping. Stops 22 fixed upon the latch members 18 engage the ends of the arm 11 and prevent the platen from being elevated beyond the position seen at Fig. 2. By lifting the bar 13, the parts are returned to normal position, and the spring 21 forces the latch over the axle 3.
- 40 After the assembled sheets are inserted around the platen, the pressure rollers 8, 9 may be thrown off by means of the usual release key 23, link 24, and rock shaft 25. These release parts being well known need no further description. The release key remains down in its operative position in the usual manner. The sheets may then be adjusted accurately by means of the usual scale in front of the platen, or otherwise, and then the release key 23 returned to normal position. Thus the platen may be elevated to permit the introduction of paper, and then returned to normal position, and subsequently the pressure rolls may be thrown off to permit the adjustment of the paper.
- At Fig. 3 is shown the usual line-spacing mechanism; the platen axle being shown in section in normal position, and in dotted lines in elevated position.
- 60 The cam lever 26, which is used to disengage the line space detent 27, may be provided with a closed slot 28 to inclose and act upon the pin 29 of said roll 27. The cam being in this form, there is no opportunity for accidental disengagement of said pin from

the control of the cam by reason of the up and down movements of the platen and line-spacing wheel which is rigidly connected to the platen.

Mounted upon the bar 13 are two pairs of pressure rolls 30, 31, the former between the latter. Each roller is adjustable independently of the other along said bar by means of brackets 32, and the latter are mounted to turn upon the bar 13, which is cylindrical in form, so that when it is desired either to insert the paper downwardly in front of the platen or to adjust the paper after introduction, said rolls may be cast off from the platen. These rolls bear normally against the upper front side of the platen, a little above the printing line.

The outer rolls 31 may remain in operative position to hold wide sheets of paper, while the inner rolls 30 permit adjustment of narrow sheets of paper to the proper positions in relation to the wide sheets. Normally the rolls are held against the platen by springs 33, which bear upon the ends of little rolls 34, and press the latter into a groove 35 extending longitudinally of the bar 13.

The line space wheel 27^a is operated by a spring pawl 39, which as usual stands away from the wheel to permit backward rotation of the latter. It will be seen that there is sufficient clearance between the pawl and the wheel to enable the latter to swing up without engaging the pawl. As usual in the Underwood machine, said pawl is operated by a lever 36, having a short arm 37 to engage a slide 38, the latter carrying the pawl 39 and provided with a returning spring 40. The platen and line space wheel may thus be thrown up independently of the mechanism that rotates the line space wheel. The roll 27 may remain in engagement with the line space wheel during the upward and downward movements of the latter without objection.

Many variations may be resorted to within the scope of the invention, particularly in the manner of hanging a bail or other frame upon the platen frame (or traveling frame) for lifting the platen; and portions of my improvements may be used without others.

Having thus described my invention, I claim:

1. In a typewriting machine, the combination with a platen and a platen axle, of a frame supporting said platen, a pair of locks engaging the axle at the ends of the platen, a pair of three-armed members hinged at the ends of the platen frame, a bar rigidly connecting one pair of the arms of said three-armed members, means upon another pair of said arms for engaging the platen axle to lift the platen, and means connected to the remaining pair of said arms for releasing said locks.
2. In a typewriting machine, the combination with a platen and a platen axle, of a frame supporting said platen, a pair of locks engaging the axle at the ends of the platen, a pair of three-armed members hinged at the ends of the platen frame, a bar rigidly connecting one pair of the arms of said three-armed members, means upon another pair of said arms for engaging the platen axle to lift the platen, and means connected to the remaining pair of said arms for releasing said locks.

tion with a platen and a platen axle, of a frame supporting said platen, a pair of locks engaging the axle at the ends of the platen, a pair of three-armed members hinged to the ends of the platen frame, a bar rigidly connecting one pair of the arms of said three-armed members, means upon another pair of said arms for engaging the platen axle to lift the platen, and means connected to the remaining pair of said arms for releasing said locks; said locks being spring-pressed and pivoted, and being connected by links to the last-mentioned pair of arms in such a manner that when the platen is elevated the spring-pressed locking members serve to hold the platen in its elevated position; means being provided for limiting the upward movement of the platen. 15
